UNITED STATES PATENT OFFICE.

OLIVER M. EDWARDS, OF SYRACUSE, NEW YORK.

HINGE FOR DOORS AND LIKE MOVABLE OBJECTS.

No. 850,422.

Specification of Letters Patent.

Patented April 16, 1907.

Application filed March 16, 1905. Serial No. 250,486.

To all whom it may concern:

Be it known that I, OLIVER M. EDWARDS, a citizen of the United States, residing at Syracuse, county of Onondaga, State of New York, have invented certain new and useful Improvements in Hinges for Doors and Like Movable Objects, of which the following is a full, clear, and exact description, reference being had to the accompanying drawings, forming a part of the same.

My invention relates generally to the manufacture of hinges for doors and similarly-mounted objects which turn on pivotal connections or means in moving from one position to another, and has for its object generally the construction of hinges of equal or greater strength, of improved appearance, and which are more readily and cheaply made than the hinges heretofore in use; and it consists in the construction and combination of the parts or devices hereinafter set forth, and particularly pointed out in the claims, which form a part of this specification.

My invention is particularly well adapted to the providing of hinges for platform trap-doors of railway-cars or similarly-mounted movable parts and which may be subjected to extra hard usages from one cause or another and require that the hinge and door or other movable part be readily and firmly secured together. One form of such hinges is seen in reissued Letters Patent No. 11,844, dated August 7, 1900, granted to George E. Seymour and Ferdinand Kahler. As there shown the hinge is made to receive a spring by which the door may be actuated in one direction, or its movements are more or less controlled. While this feature is no necessary part of the present invention, it is one that is readily provided for in my improved hinges—that is, my invention provides a form of hinge in which a spring or springs may be used, as shown in this Seymour and Kahler reissued patent, with little additional expense, if it is desired to thus utilize the space within the hinge for this purpose, whether such hinge be of the particular form shown in such patent or of some other special form. Hinges of this general character may have the male member or members of the pivotal means fixedly or otherwise secured to the door, or the female member or members may be thus secured to the door, as one chooses. As shown in this reissued patent the male members of the hinge are

formed integral with the portions rigidly affixed to the door, and hence these portions of the hinge are usually formed by a single piece of material—for instance, as a casting. 60 In practice it has been found very difficult to produce hinges of this character of sufficient strength without either using expensive materials and a comparatively moderate amount of labor in getting the hinge in proper shape 65 or using less expensive materials and an excessive amount of labor to accomplish this result. The hinge in either case is an expensive one to construct and apply.

My improved hinge is constructed from 70 different pieces of material to a greater extent than heretofore, and it may have the portion secured to the door constructed out of different kinds of material, if so desired. For instance, the pivotal portions may be made 75 from material of one kind well adapted for strength and long wear by the use of a comparatively small amount of that kind of material, and other parts may be made from material of another and cheaper kind well 80 adapted to serve its intended purpose without an undue amount thereof being used.

Like letters of reference wherever they occur indicate corresponding parts in the several figures of the drawings.

Figure 1 shows in plan view one embodiment of my invention, where portions of a door are shown mounted, as in a car-platform, and with the hinge members or pivotal means attached to the platform exposed to view by breaking away portions thereof. Fig. 2 shows in edge view the door removed from the platform. Fig. 3 illustrates the immovable and female member of the hinge mounted at the left of Fig. 1. Fig. 4 illustrates the male and movable member, which coacts with the member seen in Fig. 3, but detached from the rest of the hinge. Fig. 5 illustrates the female member attachable to the hinge and door at the right-hand edge thereof. Fig. 6 illustrates the male member to be attached to the platform or other portion to which the door or other movable part is to be hinged. Fig. 7 illustrates in plan view a modified form of hinge construction with the door or hinged part partially broken away, and wherein the male member attached to the door at the left-hand edge is hollow, and the space within the hinge is adapted to receive a spring, springs, or other desired part somewhat as the spring is received in the hinge of the construction shown 100 105 110

in this reissued Patent No. 11,844. Fig. 8 shows in edge view that which is seen from the left of Fig. 7. Fig. 9 shows in edge view that portion of the hinge which receives the pivotal members of the hinge which move with the door and to which the latter is secured and which for convenience may be termed the "shell" or "receiving" portion. Fig. 10 shows the hollow male portion of the hinge seen at the left of Fig. 7 when detached and separate from the receiving or shell portion of the hinge. Fig. 11 shows that member of the hinge seen at the right of Fig. 7, when the same is separated from such receiving portion. Fig. 12 shows in end view the part seen in Fig. 11, which, as shown, is adapted to receive one member of the hinge somewhat of the form shown in Fig. 6 and also one end of a spring or springs, such end or ends being received in the squared opening seen. Fig. 13 shows in longitudinal section the part of the hinge seen in Figs. 11 and 12. Fig. 14 shows in edge view a modified form of receiving or shell portion. Fig. 15 shows in edge view another modified form or shape of shell or receiving portion. Fig. 16 shows a form of male-hinge member adapted to be received in the shell portion seen in Fig. 15. Fig. 17 illustrates the manner of attaching the hinge when completed to the door or other hinged member of the structure to which it is to be applied.

The different portions of these hinges may be constructed in any known or desired manner, accordingly as individual circumstances seems to make it most convenient or desirable. Where the receiving or shell portion is to be of the form seen in Figs. 1, 2, 7, 8, 9, 15, and 17, I prefer to form such portion by forming it into shape out of sheet metal by means of dies of suitable form to give the desired form or shape to such portions. This may be accomplished by known or desired methods of stamping metal. Under circumstances where it is thought that the best results can be accomplished by the use of material of varying thickness these shell portions may be given the desired shape or form by the use of any desired means or method conveniently at hand, which is adapted for the purpose. In practice I have found it satisfactory to construct the parts or members which are to be secured to the receiving or shell portion by the method of casting and using material of good-wearing qualities, both as to strength and otherwise, as these parts require but a small proportion of the weight of material composing the shell portion.

In Figs. 1 to 6, inclusive, A represents the door or other part which is to be hinged in position for use, and B represents the platform or other structure to which the door or other part is to be hinged. The receiving or

shell portion of the hinge is designated C, and as here shown is secured to the door by being received between two extending or flange portions c c', with fastenings passing through such flange portions and entering the portion of the door thus received by such portions. D D' represent the pivotal portions of the hinge which are received by the shell portion. E E' represent the pivotal portions of the hinge mounted upon the platform or other structure to which the hinge is to be applied, which portions coact with the portions received by the shell portion as hinges usually act. The pivotal portions of the hinge here shown, which are attached to the shell portion and move with the door as it moves, are designated as D and D', respectively, and the portions of the pivotal means mounted on the platform or other structure, with which the parts D and D' coact, are 85 designated E and E', respectively, the parts D and E', respectively, being male members of the hinge and the parts D' and E, respectively, being the female members thereof. These several male and female members of 90 the hinge form the pivotal means by which the door or other part is hinged to the structure in position to be used.

When the shell portion of the hinge has been suitably formed by stamping, with dies or otherwise, and the parts D and D' have been suitably constructed to be received by the shell portion, they are placed in proper position in such receiving or shell portion and secured therein by any suitable and desired means, as by riveting, in the manner shown in Figs. 1 and 2 of the drawings, where the rivets x pass entirely through such receiving portion and the parts D and D', suitable openings being made to admit such rivets.

That portion of the door or other part to be hung which is to swing to the least extent is received between the flange portions c and c' of the portion C, and any suitable or desired fastenings may be employed to secure the same together, such as screws, as indicated in Fig. 2, which will firmly fasten the door and hinge together. The door is then pivotally mounted to the platform or other structure by the parts E and E' being secured in place thereon with the parts e and e' in proper coacting relations with the parts d and d' of the hinge.

If it is desired to utilize the space between the shell portion and the door and use a 120 spring or springs, connecting at one end to the door and at the other to the platform by arranging such spring or springs on the axial line of the hinge, as shown in said reissued Patent No. 11,844, or otherwise, it can be 125 done by constructing the parts of the hinge received by the shell portion, as seen in Figs. 7 to 13, inclusive, and then securing them to the shell portion, as seen in Fig. 7. As shown in these Figs. 7, 8, and 9, the shell por-

tion is of slightly different form or shape from the corresponding portion of the hinge shown in preceding figures; but for the purposes of the present invention the two forms 5 are substantially the same, because the invention does not reside in any mere shape or form of the several individual parts which go to make up the hinge. As seen in Figs. 8 and 9, this shell portion is constructed of metal of 10 substantially uniform thickness, as in the case of sheet metal, and it will preferably be made from such metal, if a hinge of the greatest strength for the least weight of a given metal—such, for instance, as is commonly 15 known as sheet-steel—is desired. Metal, as is well known, has to be sufficiently ductile in order to be formed into shapes, such as shown herein, by means of dies, and such metal is compressed and somewhat hardened by the 20 action of the dies thereupon in the shaping-up operation, and this renders the shell portion of the hinge stiffer than in the case of metal not thus compressed and hardened. Hence material of a less thickness for a given 25 amount of strength is obtained by thus forming such portion from sheet metal. A' represents the door or other hinged part, C' the shell portion of the hinge, c² and c³ the flange or extending portions of the shell or receiving portion, one of which flanges c³ is of greater 30 extent than the other, and D² and D³ represent the pivotal parts of the hinge to be received by such shell portion C'. Pivotal portion D² is constructed with an opening d⁴ longitudinally thereof, as indicated in Figs. 7, 35 8, and 10, having a male pivotal portion, as in the case of portion D, seen in preceding figures, which is to be received by any suitable form of female member—such, for instance, 40 as seen in reissued Patent No. 11,844, or in Figs. 1 and 4 of the drawings herein, and by which the door is pivotally secured to the structure wherein used. This opening, as d⁴, in this part D² permits a spring or springs to 45 extend therethrough and be connected to the platform at one end and to the door at the other end axially of the hinge of the door or other hinged part. This in many cases is of considerable importance, as it permits of the 50 placing of the spring or springs in a manner to very effectively act on the door and to be concealed from view with large economy of space. An opening d⁵, preferably of rectangular shape, is formed in the part D³, as 55 indicated in Figs. 12 and 13, to receive one end of a spring or springs of the general character indicated in said reissued Patent No. 11,844, so that as the door turns on its hinge 60 with it, putting such spring or springs under increased tension as the doors move in one direction to return such door in the opposite direction. Thus this part D³ is adapted to thus receive one end or ends of a spring or 65 springs, and it is also adapted to receive the

male member in the opening d³ in a similar manner to that the member e' of the part E', attached to a platform, is received by the opening d' in the part D'. (Seen in Figs. 1, 5 and 6 of the drawings.)

If desired, metal of differing thicknesses instead of uniform thickness may be used in practicing the present invention—as, for instance, as seen in Fig. 14, where the shell portion C² is formed with the extending or flange portion c⁴ thicker than any other part of such shell portion. This shell portion C² is adapted to receive the door and the parts, as D² and D³, the same as is the case with the shell portion C'. (Seen in Figs. 7, 8, and 9.) This shell portion C² may be formed in any desired manner by the use of any kind of means thought most convenient for the purpose, whether it be by forcing metal under great pressure through a die or by rolling a sheet or plate of differing thicknesses and then bending the same into the desired shape by well-known processes or methods of manipulating metals.

Other forms of shell portions may be employed, if desired, and such portions may be attached to the seat, door, or other part to be hinged in any desired manner, one of which is seen in Figs. 15 and 17, wherein A² represents the seat, door, or other part, C³ the shell portion, and D⁴ the pivotal part having the male member d⁶, which is to be received and secured to the shell portion, which in turn is to be secured to the door or other part. As seen in Fig. 17 the shell portion C³ is attached to one surface of the door or seat by two outstanding flanges or extending portions and bolts or fastening devices passing through both the door and the flanges of such portion. As here seen the part D⁴ is received 105 within the shell portion and is secured thereto by rivets x², as shown, or such part may be secured to the shell portion in any other desired manner or by any other means.

These hinges are adapted for use in connection with platform trap-doors or other parts which are to be moved from one position to another whether such parts move in one direction or another relatively to the main structure to which they are to be hinged or pivotally mounted. Hence the brief term "door," as used in the claims hereunto annexed, includes all such parts which are to be hinged to a structure and move from one position to another as a door moves.

I have herein shown and described differing forms or shapes of shell portions with differing forms or shapes of parts to be received thereby and secured thereto and those forms or shapes will naturally suggest to the minds of others skilled in the art still other forms or shapes, and hence I do not care to limit myself to the specific shapes or forms shown, but wish to include all forms or shapes which serve the functions or accomplishes the work 125 130

served or accomplished by such specific forms or shapes thus shown, in substantially the manner herein set forth.

What I claim as new is—

- 5 1. In a hinge the combination, substantially as set forth, of a shell portion adapted to receive pivotal means, pivotal means adapted to be received by and be secured to such portion so as to move therewith as such portion moves, and other pivotal means adapted to coact with the pivotal means secured to the shell portion.
- 10 2. In a hinge the combination, substantially as set forth, of a shell portion adapted to be attached to a door and to receive pivotal means to be directly secured to such portion, pivotal means adapted to be received by and secured to such portion, and other pivotal means adapted to be secured to a structure and hinge the door thereto.
- 15 3. In a hinge the combination, substantially as set forth, of a shell portion provided with flange portions by which the shell portion may be attached to a door, pivotal means directly secured to the shell portion, and other pivotal means adapted to be secured to a structure and hinge the door thereto.
- 20 4. In a hinge the combination, substantially as set forth, of a shell portion provided with flange portions adapted to receive a portion of a door between them to directly secure the door thereto, pivotal means secured to the shell portion, and other pivotal means adapted to be secured to a structure and hinge the door thereto.
- 25 5. In a hinge the combination, substantially as set forth, of a shell portion provided

with two substantially parallel portions between which separate portions of material to 40 form pivotal means may be received and secured thereto, pivotal means composed of pieces of material separate from the shell portion adapted to be secured to the parallel portions thereof, and other pivotal means 45 adapted to be secured to a structure and hinge the door thereto.

6. In a hinge the combination, substantially as set forth, of a shell portion adapted to receive two pivotal members, one of 50 which is provided with an opening longitudinally of the same adapting such member to receive another part, and other pivotal means adapted to be secured to a structure and hinge such shell portion thereto. 55

7. In a hinge the combination substantially as set forth, of a shell portion formed up from sheet metal by bending and adapted to receive pivotal means, pivotal means adapted to be received by and be secured to 60 such portion, and other pivotal means adapted to coact with the pivotal means secured to the shell portion.

8. In a hinge the combination, substantially as set forth, of a shell portion formed 65 up from sheet metal of differing thicknesses by bending and adapted to receive pivotal means, pivotal means adapted to be received and secured to such portion, and pivotal means adapted to coact with the pivotal 70 means secured to the shell portion.

OLIVER M. EDWARDS.
